TERMINAL BOX FACE PLATE ASSEMBLY

Kenneth Reiner, Los Angeles, Calif., assignor to Reiner Industries, Inc., Pico Rivera, Calif., a corporation of California

Filed Apr. 3, 1961, Ser. No. 64,584

Term of patent 14 years

(Cl. D26—13)

FIG. 1.

FIG. 2.

FIG. 3.

FIG. 4.

FIGURE 1 is a perspective view of a terminal box face plate assembly embodying my new design.

FIGURE 2 is a front elevation of the terminal box face plate assembly shown in FIGURE 1.

FIGURE 3 is a side elevation of the terminal box face plate assembly shown in FIGURE 1.

FIGURE 4 is a bottom view of the terminal box face plate assembly shown in FIGURE 1.

I claim:

The ornamental design for a terminal box face plate assembly, as shown.
